UNITED STATES PATENT OFFICE.

JAMES R. WELTON, OF SCRANTON, PENNSYLVANIA.

THREAD CLEANER.

Application filed November 2, 1927. Serial No. 230,587.

This invention relates to improvements in thread cleaners, and more particularly to a novel thread cleaner of the type employed to clean the thread as it is being wound on a 5 quill or bobbin, preparatory to weaving. The device is positive in its action in catching or removing snarls, bad knots, wax, gum or the like.

Devices of this character usually include 10 a slotted element which may be in the form of an integral slotted plate, or be made up of opposing jaws spaced apart to provide the slot or clearance through which the thread travels.

Both types have been found to have disadvantages in actual practice. In the integral plate type, separate plates must be employed for threads of different thicknesses, while the plate made up of two jaws, has not been 20 entirely practical, owing to the fact that the movable jaw will loosen, due to the vibration of the machines, and this will affect the operation of the cleaner. Furthermore, the movable jaw type of cleaner may be readily 25 tampered with by the operator after it has been properly adjusted, and this also affects the operation of the cleaner.

The primary object of the present invention is to provide a movable jaw type cleaner, 30 in which the movable jaw may be positively locked in position, a part of this locking being accomplished by special screws which require a special wrench for their manipulation; this feature preventing the operator 35 from tampering with the device.

Another object of the invention is to provide a cleaner of this character with special means for mounting the same on the ordinary supporting rods of the machine, such means 40 permitting instantaneous detachment of the device when necessary.

A still further object is to furnish a cleaner of this type, in which the movable jaw may be readily adjusted by an authorized person, 45 for the purpose of taking care of threads of different thicknesses, and which may be expeditiously locked in position after an adjustment has been made.

With the foregoing objects outlined, and 50 with other objects in view which will appear as the description proceeds, my invention consists in the novel features hereinafter set forth in detail, illustrated in the accompanying drawing, and more particularly pointed 55 out in the appended claims.

Referring to the drawings,

Fig. 1 is a side view of my improved device.

Fig. 2 is a front view of the same.

Fig. 3 is a plan view, partly broken away. 60

Fig. 4 is a perspective view of the main parts of the cleaner, shown apart from each other.

In the drawings, 1 designates the usual supporting rod of the machine, and 2 a rearwardly extending supporting arm on the bracket 3. The arm 2 is provided with a semi-cylindrical notch 4, which embraces the rod 1, and is rigidly held in contact with the rod by means of a clamp 5. This clamp is 65 provided with forwardly extending arms 6 terminating in flanges 7 which project toward one another. The distance between the flanges 7 is greater than the diameter of the rod 1, so that the clamp may be readily 70 slipped over the rod 1, and then be moved axially along the rod to grasp the arm 2. A screw 8 is threaded in the clamp, and is adapted to impinge against the rod 1 for the purpose of drawing the flanges 7 against the 75 surfaces 9 of the arm 2, and in this way, to force the surface of the notch 4 against the rod 1.

With a clamping device of this character, 80 the cleaner will remain in position indefinitely after the screw has once been tightened, and yet, when one desires, the cleaner can rapidly be removed from the rod by simply loosening the screw 8, and then moving the arm 2 axially of the rod, while the clamp 5 85 remains in place.

The bracket 3 has an upwardly extending arm 10, and a downwardly extending arm 11. Each of these arms has an aperture to receive a screw 12 which supports a porcelain thread 90 guide 13 of known construction. Nuts 14, 95 secure the screw 12 in position.

The bracket also includes, as best shown in Fig. 4, a forwardly extending shelf 15 having a notch 16 in its central portion, and an upwardly extending flange 17 at one of its side edges. The shelf has a vertical abutment 18 at its rear, which functions as a stop for the rear ends of the jaws of the cleaning 100 plate, which will now be described.

This cleaning plate consists of a stationary jaw 19, and a movable jaw 20. Each jaw has parallel upper and lower surfaces, and parallel side edges, and the inner end of each jaw is provided with a thread receiving and 105 cleaning notch 21, and a fastening pin receiving notch 22. The forward edges 23 of the

jaws converge to facilitate the introduction of the thread into the clearance space between the inner edges of the jaws, and into the notches 21.

5 The movable jaw also has two threaded apertures 24 for a purpose hereinafter described.

In assembling the device, the stationary jaw is first placed on the shelf 15 with its outer edge abutting the inner surface of the flange 17, and its rear end engaging the abutment 18, and its notch 22 engaging a short upwardly extending post 25, fixed on the shelf 15.

15 The movable jaw 20 may then be placed on the shelf with its notch 22 in engagement with the post 25.

It is obvious that the movable jaw may be moved into substantial contact with the stationary jaw, or be slid laterally on the shelf in the opposite direction, as there is no flange similar to the flange 17 on the other edge of the shelf to prevent such lateral movement. Consequently, after all of the parts are assembled, the movable jaw may be adjusted without dismantling the structure.

The shelf and jaws cooperate with a keeper 26 which includes a plate 27 having downwardly extending legs 28, terminating in ledges 29 which project toward each other. After the jaws have been placed on the shelf, this keeper may be slid rearwardly on to the shelf, and when its rear end abuts the arm 10 of the bracket, a slot 30 in the keeper will be in alignment with the slot 16 of the shelf, and both slots will register with the clearance space between the jaws.

40 The leg 28 of the keeper has a pair of threaded apertures 31 to receive special screws 32 which can only be turned by a special tool for the purpose of causing the inner ends of the screws to impinge against the flange 17 of the shelf. When these screws are tightened, they cause the inner surface 45 of the leg 28 to abut against the unflanged edge of the shelf, as shown at 33. In this way, the keeper is locked on the shelf.

Three screws 34, 35 and 36, similar to the screws 32, are employed to lock the jaws in 50 position, and these screws also assist in locking the keeper in place as they function to draw the ledges 29 against the under side of the shelf 15.

55 One of the legs 28 of the keeper has a threaded aperture 37, and a pair of unthreaded apertures 38. Screws 39 pass through the unthreaded apertures and are threaded into the holes 24 of the movable jaw, and they function in the adjustment of the jaw and 60 also prevent the jaw from accidentally detaching itself from the keeper. A screw 40 passes through the hole 37, and impinges against the outer side edge of the jaw 20, to also assist in locking that jaw in position.

65 It will be understood that when the screw

36 is loosened, the screws 39 and 40 may be used to adjust the movable jaw into any new position, and then the screw 36 may be tightened to again lock the jaw in place.

In operation, the thread 41 is cleaned during its passage from a bobbin to a quill, and in such passage, the thread moves first through the upper guide 13, then through slot 30, the clearance space between the jaws, slot 16, and the lower guide 13, and as it contacts with the inner edges of the jaws, any loose fuzz or excess wax, gum or the like, will be scraped off. Furthermore, if a knot is encountered, the thread will break, and then the operator may remove the defect, tie the clean ends together, and continue the winding operation. The material rubbed off the thread, due to the back and forth movement of the thread in unwinding from the bobbin, will cause the material removed from the thread to feed toward the cleaning notches 21 through which it will be automatically discharged.

70 Each of the screws 32, 34, 35 and 36 is provided at its outer end with an irregular hole 75 50 which necessitates the use of a special tool for the turning of the screw.

75 From the foregoing description, it is believed that the construction, operation and advantages of the invention may be readily understood, and it is apparent that changes may be made in the details disclosed without departing from the spirit of the invention, as expressed in the claims.

80 What I claim and desire to secure by Letters Patent is:

1. In a thread cleaner, a bracket having a slotted shelf, a stationary jaw mounted on the shelf, a movable jaw slidably mounted on the shelf and adapted to be moved in a path at right angles to the slot of the shelf, toward and away from the stationary jaw to provide a clearance space in alignment with said slot, said movable jaw having parallel side edges and means for locking the jaws in 100 position.

105 2. In a thread cleaner, a bracket having a slotted shelf and a fixed post, a stationary jaw removably mounted on the shelf and having a notch engaging said post, a movable jaw 110 slidably mounted on the shelf and having a clearance space to accommodate said post, and means for locking said jaws in position on the shelf.

115 3. In a thread cleaner, a bracket having a slotted supporting shelf, a stationary jaw and a movable jaw mounted on said shelf, a keeper detachably mounted on the shelf, and means cooperating with the keeper to lock the keeper to the shelf and to lock the jaws 120 in position.

125 4. A thread cleaner comprising a bracket having a slotted supporting shelf, stationary and movable jaws carried by the shelf, a keeper slidably mounted on the shelf, and 130

means cooperating with the keeper to lock the latter to the shelf and to lock the jaws in position.

5. In a thread cleaner, a bracket having a shelf, stationary and movable jaws carried by the shelf, a keeper cooperating with the shelf, means for locking the keeper on the shelf, and means cooperating with the keeper for adjusting the movable jaw.

10 6. In a thread cleaner, a bracket having a supporting shelf provided at one edge only with a flange, a stationary jaw mounted on the shelf and abutting against said flange, a movable jaw slidably mounted on the shelf, 15 a keeper detachably connected to the shelf, the keeper and shelf being slotted to permit the passage of a thread, means for locking the keeper on the shelf and the jaws in position, and means cooperating with the 20 keeper to permit adjustment of the movable jaw without removal of the keeper.

7. In a thread cleaner, a bracket having a stationary shelf provided with a slot and a flange, a flat stationary jaw removably

25 mounted on the shelf and engaging said flange, a flat movable jaw mounted on the shelf and slidable rectilinearly transversely of the shelf in a path arranged perpendicularly to the slot, and means for locking the jaws to the shelf.

30 8. In a thread cleaner, a bracket having a slotted supporting shelf, a stationary jaw removably mounted on the shelf, an adjustable jaw slidably mounted on the shelf and movable in a path at right angles to the slot 35 of the shelf, the adjustable jaw having parallel side edges, and means for locking said jaws in position.

9. In a thread cleaner, a slotted bracket having a stationary shelf provided at one 40 side edge with an upwardly extending flange, a stationary jaw mounted on the shelf and abutting against said flange, a movable jaw slidably mounted on the shelf, means for moving the last mentioned jaw in a path ar- 45 ranged at right angles to said slot, and means for locking the jaws in position on the shelf.

JAMES R. WELTON.
